THERMOSTAT HOUSING OR THE LIKE

Edward P. Stucka, Deerfield, Ill., assignor to
Honeywell Inc., Minneapolis, Minn.

Filed Sept. 30, 1971, Ser. No. 185,465

Term of patent 14 years

Int. Cl. D10—04

U.S. Cl. D52—7 R

FIG. 1

FIG. 2

FIG. 3

FIG. 1 is a top, left, front perspective view of a thermostat housing or the like showing my new design, the bottom being substantially a mirror image of the top;

FIG. 2 is a front elevational view thereof;

FIG. 3 is a left-side elevational view thereof, the right side being a mirror image thereof.

I claim:

The ornamental design for a thermostat housing or the like, substantially as shown and described.
